TWIST-OFF SAFETY DEVICE

Filed May 29, 1929

UNITED STATES PATENT OFFICE

PAUL YUNGLING, OF LOS ANGELES, CALIFORNIA

TWIST-OFF SAFETY DEVICE

Application filed May 29, 1929. Serial No. 366,909.

This invention relates to a device for use in deep well drilling and has for its primary object the provision of a device which may be inserted in a string of drill pipe and will prevent its parting in the event of a twist-off or break occurring. Other objects are the provision of a device of this character which is rugged and not subject to deterioration.

10 Twist-offs while drilling a well have been found to occur with greatest frequency within the first three joints (approximately sixty feet) of drill pipe, above the drill collar. Wells are frequently drilled through soft or 15 caving formations and, due to natural caving and the erosion of the circulation fluid, have pockets and portions which are of much greater diameter than the normal size of hole. When a relatively short piece of pipe breaks 20 off under such conditions, it falls to one side of the hole, and makes a very difficult fishing job, as it must be first caught, and then straightened up before it can be removed from the hole. This device is therefore intended to be used immediately above the drill 25 collar although it may be placed anywhere else in the string deemed advisable.

A preferred form of my invention by means of which I accomplish the aforementioned objects, as well as other objects, is illustrated in the accompanying drawing in which:—

Fig. 1 is an axial section through my twist-off safety device showing it placed in a string 25 of drill pipe. Figs. 2, 3 and 4 are sections taken on correspondingly numbered planes of Fig. 1; and Fig. 5 is a section through a drilling well, showing the drill pipe and bit in operating position.

40 Referring with more particularity to the drawing, the lower portion of the usual drill pipe is indicated by A and a drilling tool of any desired type is indicated by B. My device, generally indicated by C serves to connect the drill pipe with the drilling tool, and is made of a number of sections of pipe 8, connected by couplings 9, and connected to drill pipe A by a sub 11 at the top. A drill collar 12 of special form is secured at 45 the bottom, and is adapted to receive the drill-

ing tool B. Within pipe 8 is tubing 14, forming a housing for a steel cable 15. Secured to the upper end of tubing 14, as by a pipe coupling, is the top sleeve 16, having a conical bore. Threadedly secured to the top sleeve 55 is a cap 17, with a square top adapted to be grasped by a wrench. Within cap 17 is a cone shaped wedge 18, having a threaded stem 19 projecting through a hole in the top of the cap. A nut is provided on the stem 60 to hold the cap and wedge together during assembly.

The top sub 11 has a central bore 21 sufficiently large to permit tube 14 and its top coupling to freely pass through it. There 65 are a number of passages 22 surrounding this bore, to permit circulation to pass through the sub. The drill collar 12 has a bridge 24 adjacent the end of pipe 8 similarly provided with holes and a central bore to accommodate the lower sleeve 25. Sleeve 25 is threadedly attached to tubing 14 by a pipe coupling and has a lower end of enlarged diameter, or head 26. Head 26 is held against bridge 24 by a pair of nuts 27 and a spacer 70 28, this being keyed to the lower sleeve. A bore 29 extends through this sleeve and has a conical seat at its lower end, adapted to have the cable 15 spread and babbitted into it.

80 The device may be assembled in any convenient manner and the cable babbited in the lower sleeve, the cap 17, however, being left off. The space about the cable within the tubing is then filled with crude oil, the point 85 of the wedge 18 is inserted in the upper end of the cable which has been loosened and spread, and the wedge is forced down into the cable by screwing the cap 17 down onto the sleeve. The cable will be tightly held between the surface of the bore and the inside of the sleeve. The space about stem 19 of the wedge is then filled with babbitt and the device is ready for use. This protection of the cable is important, as deterioration would 90 be rapid if it was exposed to the fluid in the hole. Housing 14 and cable 15 and associated parts from a tie member, are secured from longitudinal movement by being secured to drill collar 12, as previously described and 95 100

extend up through the bore in the top sub 11, this serving as a guide to steady it. There is no strain on either the housing or cable until pipe 8 twists off or parts at some point. When this occurs, all parts below the break will cease to rotate, and no torsional strain can come on the housing as it is free to revolve in both the top sub and the drill collar. When the break occurs it is at once apparent to the driller who stops rotating and commences to pull the drill pipe. The portion below the break together with the housing remains on the bottom and the drill pipe with top sub will rise until the top sub engages the bottom of cap 17, when the cable 15 will serve to pull the remainder and the entire string may be brought out of the hole, the same as if unbroken.

Fig. 5 illustrates the condition mentioned in the beginning of the specification, in which the hole is considerably oversize, due to caving or some other cause. If now a break occurs at same point E without a twist-off safety device in use, the portion below the break will fall to one side of the hole as indicated at F, leading to a difficult fishing job. If the break were to occur at some point higher up, the possibility of the portion left in the hole leaning over is greatly reduced, and if the break occurred inside the casing G, it could not lean over at all. Thence the desirability of a place immediately above the drill.

What I claim is:—

1. A device of the character described comprising a tubular body having abutment members secured to the ends thereof and a tie member including a tubular housing secured against longitudinal movement and free to turn in one of said abutment members and arranged to coact with the other of said abutment members upon a severance of said body and thereby allow a limited relative movement of said abutment members, said tie member including a cable disposed wholly within and anchored to the ends of said housing.

2. A device of the character described, comprising a tubular body, an abutment member secured at one end thereof and having a bore, a tie member disposed within said body and passing through said bore and designed to slide freely therein, an abutment member secured to the other end of said body and having a bore, said tie member being disposed in said last mentioned bore and secured therein against longitudinal movement and free to turn said tie member comprising a tubular housing with sleeves attached to the ends thereof, a cable disposed therein and secured to said sleeves, and a shoulder on said housing adapted to engage one of said abutment members.

3. A device of the character described comprising a tubular body, an abutment member secured at the upper end thereof and having a bore, a housing disposed within said body

and passing through said bore and arranged to slide freely therein, an abutment member secured to the lower end of said body and having a bore, said housing being disposed therein and secured against longitudinal movement but free to rotate, sleeves secured to the ends of said housing, a cable within said housing secured in said sleeves, a shoulder on said housing arranged to engage said upper abutment member upon a predetermined separation of said abutment members, and means within said housing to prevent corrosion of said cable, there being openings through said abutment members to allow fluid to pass into and out of said body.

In witness that I claim the foregoing I have hereunto subscribed my name this 10th day of May, 1929.
